CLAIM

The ornamental design for a planter, as shown and described.

DESCRIPTION

FIG. 1 is a top front perspective view of a planter showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another right side view of the planter in an environment in which it may be used.

The broken lines in the Figures show portions of the planter or environment that form no part of the claimed design.

1 Claim, 8 Drawing Sheets

Related U.S. Application Data

a continuation of application No. 29/577,172, filed on Sep. 9, 2016, now Pat. No. Des. 814,345, which is a continuation of application No. 29/522,921, filed on Apr. 3, 2015, now Pat. No. Des. 776,127, and a continuation of application No. 29/517,034, filed on Feb. 9, 2015, now Pat. No. Des. 769,148, said application No. 29/522,921 is a continuation of application No. 29/517,034.
